UNITED STATES PATENT OFFICE

149,875

DESIGN FOR A FLOOR LAMP

William A. Hillenbrand, Franklin County, and Francis J. Burst, Batesville, Ind., assignors to Hill-Rom Company, Inc., Batesville, Ind., a corporation of Indiana

Application December 14, 1946, Serial No. 135,505

Term of patent 14 years

(Cl. D48—20)

To all whom it may concern:

Be it known that we, William A. Hillenbrand and Francis J. Burst, both citizens of the United States and residing at Franklin County and Batesville, in the counties of Franklin and Ripley, respectively, and State of Indiana, have invented a new, original, and ornamental Design for a Floor Lamp, of which the following is a specification, reference being had to the accompanying drawing, forming a part thereof.

We claim:

The ornamental design for a floor lamp, substantially as shown.

WILLIAM A. HILLENBRAND.
FRANCIS J. BURST.
